Term of patent 14 years

(Cl. D87—5)

FIG. 1

FIG. 2

FIG. 3

FIG. 4

FIG. 5

FIG. 1 is a side elevational view of a stereo tape container, showing my new design;

FIG. 2 is a side elevational view thereof showing the side opposite that shown in FIG. 1;

FIG. 3 is a top elevational view thereof;

FIG. 4 is an end elevational view thereof; and

FIG. 5 is an end elevational view showing the end opposite that shown in FIG. 4.

The characteristic features of my design reside in the configuration of the open carrying handle and the adjacent cover portion having a flat rectangular top surface encompassed by a raised band all as shown.

I claim:

The ornamental design for a stereo tape container, as shown and described.
